UNITED STATES PATENT OFFICE.

REUBEN C. BAKER, OF COALINGA, CALIFORNIA, ASSIGNOR TO BAKER CASING SHOE COMPANY, OF HUNTINGTON PARK, CALIFORNIA, A CORPORATION OF CALIFORNIA.

WELL-CASING SPIDER SLIP.

Application filed October 9, 1924. Serial No. 742,664.

The present invention relates to improvements in well casing spider slips and has for an object to provide an improved slip which will promote a better alinement of the 5 slip around the casing and consequently a more efficient grip, while so coupling the parts thereof that the same may be readily handled and yet flex relatively so as to promote the alinement and the gripping of the 10 pipe.

A further object of the invention is to provide a device of a very simple construction which may be readily assembled and disassembled and which though made in four 15 sections, is handled substantially as two sections.

With the foregoing and other objects in view, the invention will be more fully described hereinafter, and will be more particularly pointed out in the claims appended 20 hereto.

In the drawings, wherein like symbols refer to like or corresponding parts throughout the several views,

25 Figure 1 is a longitudinal section taken through a portion of the device.

Figure 2 is a perspective view of the connecting link.

Figure 3 is a plan view of the device with 30 the plugs 26' removed.

Referring more particularly to the drawings the device consists of four sections, 5, 6, 7 and 8 all having the usual form of teeth 9 with which to grip the pipe, and formed 35 with tapering outer faces 10 to fit a similar opening in the spider whereby to guide the sections of the slip against the casing. The casing is thus held firmly while an adjoining section is screwed into the coupling.

40 Although there are four sections according to the present invention these sections are handled as two because of the fact that the companion sections 5 and 6 are coupled by the link 11 and the opposite pair of sections 7 and 8 are coupled together by the link 12. These links are the same and one such link is shown in Figure 2 as being composed of a substantially flat bar 13 of metal or other appropriate material provided with the enlarged beaded edges 14 and 15 substantially rounded in cross section and adapted to fit into sockets of similar form, said sockets being produced in the adjoining faces of the sections 5 and 6. 50 Such sockets are indicated at 16 and 17 and

slots 18 and 19 also made in the edges of the members 5 and 6 to communicate through the side walls with the slots. The sockets and slots are slightly wider than the metal of the link so that a loose motion 60 is permitted the two sections. The sockets extend only partially the length of the section as indicated in Figure 1 so as to prevent the link from dropping through. The link may be removed by simply inverting 65 the sections whereupon such link will drop out. The link couples the two sections 5 and 6 together yet permits of a radial flexibility or relative movement in the sections such as will allow the sections to accommodate 70 themselves to the contour of the pipe wall and effectively grip said wall.

Bolts or screws 20 and 21 are threaded or otherwise secured in the upper portions of the sections 5 and 6 and are provided with 75 perforated heads to receive the terminal portions 22 and 23 of the handles or bails 24 having the cylindrical grips 25 extending about the intermediate portions thereof. The extremities of the handles after passing 80 through the openings in the heads or bosses 20 are turned at substantially right angles as indicated at 26 in order to secure the handles to the sections while permitting the handles to swing. By the use of the handles 85 the two half sections may be lifted by a single workman while each half section virtually consists of two flexibly united members capable of relative adjustment.

In the use of the device the two half sections are set down about the pipe in the opening in the spider and these sections being heavy descend by gravity and cause the teeth 9 to bind into the well casing. The sections may also be beaten down and although, in the handling, two sections only are taken into account, in effect upon the pipe there are four sections which compensate for any irregularity in the surface contour of the pipe; and these four sections individually move radially toward the center of the pipe and effectively grip the wall thereof, so that there is no possibility of the pipe turning when the upper section of the casing is screwed into the pipe connecting 95 the collar or joint.

100 The use of four sections permits of a more perfect alinement around the pipe than three sections as now commonly used and the present device therefore secures a more efficient 105 110

grip on the pipe. The three section slips require the attention of two men when the slips are placed, whereas in the present case with four sections the device is handled by a single man. The link may be kept in place in the sockets by the use of plugs indicated at 26' in Figure 1. The plugs may be secured in place frictionally or by screw threading but not tight enough to prevent free play of the links.

In Figure 1 the plugs are shown as just lightly touching the upper ends of the links.

It is obvious that various changes and modifications may be made in the details of construction and design of the above specifically described embodiment of this invention without departing from the spirit thereof, such changes and modifications being restricted only by the scope of the following claims.

What is claimed is:—

1. A slip comprising a plurality of gripping sections having slots opening through adjacent walls and through the tops of the sections and sockets at the inner ends of the slots larger than the slots and openings through the tops of the sections, links flex-

ibly connecting adjacent sections composed of enlarged ends and thin webs connecting said enlarged ends, said links adapted to be slid down through the tops of adjacent sections with the enlarged ends fitting rotatably in the sockets and the webs fitting loosely in the slots, and removable means in the top portions of the sockets to hold the links therein.

2. A slip comprising pairs of gripping sections, each pair having slots opening through adjacent side walls and tops of the sections and enlarged rounded sockets connecting with the inner portions of the slots being closed at their bottoms and open at their tops, links flexibly connecting said pairs of sections composed of enlarged rounded ends and thin webs connecting said enlarged ends, said links adapted to be slid down through the tops of the sections with the enlarged ends entering said sockets and the webs fitting loosely and rotatably in said slots, removable plugs to close the tops of the sockets above said enlarged ends of the links, and a handle connected to the pair of sections.
